UNITED STATES PATENT OFFICE

FRANK J. SCHLEICHER, OF UNIVERSITY CITY, MISSOURI

DESIGN FOR A BOX

Application filed June 22, 1929. Serial No. 31,800. Term of patent 14 years.

To all whom it may concern:

Be it known that I, FRANK J. SCHLEICHER, a citizen of the United States, residing at University City, St. Louis County, Missouri, have invented a new, original, and ornamental Design for Boxes, substantially as shown in the accompanying drawing, in which—

Fig. 1 is a perspective view showing my new design of box, only relatively small portions of the various defined surface areas having their contrasting color effects indicated, the remaining portions of said defined areas involving a mere repeat or extension of the color effects indicated.

Fig. 2 is an end elevation.

The linings for colors indicate contrasting colors. The top surface of the box has a de-

fined surface area 1 that is of a contrasting color from the adjacent surface areas 2. Around the upper portion of the wall of the box is a band 3 and around the lower portion of the wall of the box there is a band 4 of contrasting colors from the intermediate band 5. The extended marginal portion 6 of the top of the box and the extended marginal portion 7 of the base of the box are of a color contrasting with the color of the bands 3 and 4. The front wall of the box extends angularly forwardly, while the rear wall extends straight from end to end of the box.

I claim:

The ornamental design for a box, substantially as shown and described.

FRANK J. SCHLEICHER.
